TILTABLE BALL GAME TABLE

James B. Rishel, Dayton, Ohio, assignor of twenty-five per cent to Walter Becker, Dayton, Ohio

Application March 7, 1947, Serial No. 733,041

5 Claims. (Cl. 273—110)

1

The present invention relates to games and, more particularly, to games comprising a board or table.

Numerous games of the board or table type are known which may be played by one or more persons and in which the object consists in moving a ball or the like from one end of the board or table to a predetermined point at the other end of the table while various obstacles are placed in the path of the ball to be moved. One of the best known games of this type is the so-called pin ball machine in which a plunger on one side of the board pushes a ball to one end of an inclined board from where the ball rolls to the other end of the board while hitting various obstacles on its path. However, the drawback of this type of games consists in that once the ball starts its movement on the inclined board, it is completely out of the player's control and thus does not give him full satisfaction.

It is, therefore, an object of this invention to provide a game of the board or table type which will overcome the above mentioned drawback.

It is another object of this invention to provide a game of the board or table type which will permit to tilt the board or table at will in at least one direction.

A further object of the invention consists in the provision of a game of the above mentioned type in which the table or board is tiltable in longitudinal direction as well as in transverse direction thereto.

Still another object of this invention consists in the provision of a game of the board or table type having obstacles mounted thereon some of which are effective in one direction while other obstacles are effective in the opposite direction only, means being provided operable to limit the tilting movement in a longitudinal direction of the table or board so that only one end can be tilted from the horizontal plane upwardly.

It is a still further object of this invention to provide a game as set forth in the preceding paragraph, in which the limitation of the tilting movement of the board or table in longitudinal direction is brought about automatically but can selectively be applied to either end of the board or table.

These and other objects and advantages of the invention will appear more clearly from the following description in connection with the accompanying drawings in which:

Figure 1 is a top view of the game according to the present invention.

Figure 2 is a longitudinal section taken along the line 2—2 of Figure 1.

2

Figure 3 represents an end view of the game according to the invention, said view being taken along the line 3—3 of Figure 1.

Figure 4 is a section along the line 4—4 of Figure 2.

Figure 5 represents a section along the line 5—5 of Figure 2, and

Figure 6 shows a partial side view of the device according to the invention, while the play board is in one of its inclined positions.

Referring now to the drawings, the structure shown herein comprises a play board, generally designated 10, which in the specific example illustrated in the drawings represents a foot ball field. To this end, the board 10 is divided into two equal sections each having a goal 11 and 12 respectively, while obstacles 11a, 11b, 11c, 11d and 12a, 12b, 12c and 12d are arranged all over the field. As will be clear from Figure 1, the obstacles 11a, 11b, 11c and 11d are effective in one direction as protection for the goal 11, whereas the obstacles 12a, 12b, 12c and 12d are effective in the opposite direction as protection for the goal 12.

The board 10 is provided with ears 13 and 14 (see Figure 4) which are pivotally connected by means of pivots 15 and 16 with a cross-shaped member generally designated by the reference numeral 17. This cross-shaped member 17 is provided with hinge portions 18 and 19 arranged at a right angle to the ears 13 and 14 and is pivotally connected by means of pivots 20 and 21 to hinge portions 22 and 23 respectively. Thus, the pivots 15 and 16 allow the play board to tilt about the axis defined by said pivots, whereas the pivots 20 and 21 allow the play board 10 to tilt about an axis transverse to the axis defined by the pivots 15 and 16.

The hinge portions 22 and 23 form a part of a support 24 which, according to the structure shown in the drawings, may rest on a table 25. It is, of course, understood that the support 24 may have any desired shape and may, if desired, rest directly on the floor.

The support 24 is provided with two oppositely located lugs 26 and 27 to which are fastened in any convenient manner leaf springs 28 and 29 respectively. These springs are substantially equal and symmetrically arranged with regard to the axis passing through the pivots 20 and 21, so that the springs 28 and 29 continuously tend to move the cross-shaped member 17 and thereby also the play board 10 into and to hold the same in such a position that the play board 10 is not laterally inclined relative to the table 25.

In order to enable the player or players to tilt the member 17 about the axis passing through

the pivots 20 and 21, the member 17 has connected to each end thereof a V-shaped arm 30 and 31 respectively with arms 30a, 30b, and 31a, 31b. Thus, by grasping the arms 30a and 30b or 31a and 31b and swinging the arm 30 or 31 toward one side or the other, the player will cause the cross-shaped member 17 and thereby also the playboard 10 to incline correspondingly. The lateral inclination of the play board 10 will be limited by the springs 28 and 29 to a predetermined maximum angle.

Pivotedly connected to each end of the play board 10 by means of pivots 32 and 33 is a manually operable lever 34 and 35 respectively. Each lever has associated therewith two abutments 36a, 36b and 37a, 37b which limit the angle over which these levers can be moved. Each lever has furthermore associated therewith a spring 38 and 39 respectively, of which the spring 38 continuously urges the lever 34 to abut the abutment 36b as indicated in dot-dash lines in Figure 5. Similarly, but in diametrically opposite arrangement, the spring 39 continuously urges the lever 35 into abutment with the abutment 37b.

Each of the levers 34 and 35 has a nose 34a and 35a each of which is adapted to cause its lower surface to engage the upper surface of the cross-shaped member 17. However, the arrangement is such that at one and the same time the lower surface of only one nose can engage the upper surface of the cross-shaped member 17, while the other nose occupies a position on one side of the cross-shaped member. This is clearly illustrated in Figure 6 in which the left hand side of the board 10 is up while the right hand side of the board is down. While in this position the left hand side of the board cannot be moved farther downwardly, it can, however be moved upwardly with the result that the right hand end of the board can be lowered further. Thus, by swinging either lever 34 or 35 in the vertical plane, the board can be tilted longitudinally, so as to increase the angle of inclination over that shown in Figure 6. Simultaneously, if desired, the board can be tilted laterally by actuating either one of the V-shaped arms 30 or 31.

If instead of the arrangement of Figure 6, it is desired to have the left side of the board lower than the right side, it is merely necessary to swing the lever 34 from its dot-dash position in Figure 5 into its full line position of Figure 5 and then to swing the lever 34 downwardly. As a result thereof, the nose 35a will clear the side of the cross-shaped member 17, and as soon as this happens, the spring 39 will bring the nose 35a into alignment with the adjacent portion of the member 17, thereby automatically blocking a return of the right hand end of the board 10 into the position shown in Figure 6 until the lever 35 is shifted laterally by hand.

Referring to the particular example shown in the drawing, the game may be played as follows:

It may be assumed that the board 10 is being held by one or both players in the position shown in Figure 2, and that a ball is placed in the slight depression 40 provided at the center of the board 10. It may further be assumed that the player at the left side of board 10, which may be called the first player, is going to start the game with the intention to get the ball into the goal 12. The other player, which may be called the second player, will try to stop the ball before it reaches the goal 12 by causing the ball to get caught in any one of the obstacles 12a, 12b, 12c or 12d. To

this end, the first player grasps the handles 30a and 30b, whereas the second player grasps the lever 35. The second player now swings the lever 35 so as to bring the nose 35a out of alignment with the adjacent ridge of the cross-shaped member 17 and swings the lever up and down, while the first player by actuating the V-shaped arm 30 through the handles 30a and 30b tilts the board 10 laterally. In other words, the second player or the player on the defensive tilts the board longitudinally, while the first player or player on the offensive tilts the board laterally.

It should be noted that the noses 34a and 35a associated with the levers 34 and 35 are preferably so dimensioned that, once one nose is in its effective blocking position, the board is slightly longitudinally inclined downward toward the player on the defensive, so that the ball will always have the tendency to roll toward the player on the defensive. It is, therefore, the object of the player on the defensive to effect a quick longitudinal tilting movement when the ball is in front of an obstacle open toward the player on the offensive such as the obstacles 12a, 12b, 12c and 12d. When the ball is caught in one of these obstacles, the direction of moving the ball is reversed, i. e. the first player becomes the player on the defensive, and the second player becomes the player on the offensive with the aim to bring the ball into the goal 11. Therefore, the lever 34 is now unblocked by swinging it laterally and then pressing it downwardly whereupon the lever 35 automatically moves into its blocking position. The board is now inclined so that the lower end 35 is adjacent the first player, and the play may be continued in the manner described above but in reverse direction. When a goal is made, the play will again be started from the center, whereas, when no goal is made and the ball is stopped by one of the obstacles, the course of the ball may be reversed from the last stop or whatever rules may be agreed upon.

It is, of course, understood, that the present invention is, by no means, limited to the specific construction illustrated in the drawings but also comprises any modifications within the scope of the appended claims. For instance, if desired, the support 24 may be provided with legs to rest directly on the floor. Furthermore, the shape of the play board may be oval or of any other configuration. Also the obstacles may be of any desired type, or may even be so arranged as to light up when hit, or to actuate any desired type of signal.

What I claim is:

1. A tiltable ball game table comprising in combination, a playing board, obstacle means arranged in spaced relationship on said board, supporting means for said board, connecting means connecting said board to said support so as to allow lateral and longitudinal tilting movement of said board, first manually operable means arranged for tilting said board laterally only, second manually operable means independent of said first operable means and arranged for tilting said board longitudinally only, abutment means associated with said connecting means, yielding means continuously urging said second manually operable means into the path of said abutment means to thereby limit the upward tilting movement of one end of said board, said second means being shiftable manually against the thrust of said yielding means and out of the path of said abutment means to allow further upward tilting movement of said one end.

2. A tiltable game table comprising in combination, a board, first obstacle means arranged in spaced relationship on said board and adapted to catch and stop a ball in its movement from one end to the other end of said board but not vice versa, second obstacle means arranged in spaced relationship on said board but effective in a direction opposite to the direction of effectiveness of said first obstacle means, supporting means for supporting said board, joint means connecting said supporting means with said board so as to allow swinging movement of said board laterally and longitudinally, first tilting means operatively connected to said board for tilting said board longitudinally only, second tilting means operatively connected to said board and operable simultaneously with, but independently of said first tilting means for tilting said board laterally only, thereby making interference of one tilting movement by the other tilting movement impossible, and blocking means connected to said first tilting means and normally preventing movement of said board into a horizontal plane, said first tilting means being operable manually to move said blocking means into an ineffective position to thereby allow movement of said board into a horizontal plane.

3. A tiltable game table comprising in combination, a board, first obstacle means arranged in spaced relationship on said board and adapted to stop a ball moving from one end of said board to the opposite end thereof, second obstacle means arranged in spaced relationship on said board but effective in opposite direction to the direction of effectiveness of said first obstacle means, supporting means for said board, universal joint means connecting said board with said supporting means, first means for effecting tilting movement of said board only in the longitudinal direction thereof, second means operable simultaneously with said first means but independently thereof for tilting said board laterally only, thereby preventing interference of said longitudinal tilting movement by said lateral tilting movement and vice versa, and means movably connected to said board and operable to move into the longitudinal tilting path of said board to thereby prevent tilting movement of said board into a horizontal plane.

4. A tiltable game table comprising in combination, a board, obstacle means arranged in spaced relationship on said board so as to prevent a ball from moving in a straight line from a point at one end of said board to a straightly opposite point at the other end of said board,

supporting means for said board, means connecting said supporting means to said board so as to allow independent tilting movements of said board simultaneously in longitudinal direction and transverse thereto, manually operable means connected to said board for tilting said board in longitudinal direction thereof, abutment means operatively connected to said manually operable means and movable into an effective position for limiting the longitudinal tilting movement of said board to a predetermined minimum angle relative to a horizontal plane, said abutment means being adapted selectively to be moved into an ineffective position and yielding means in operative engagement with said abutment means and operable automatically to move said abutment means into effective position in response to a predetermined tilting movement of said board relative to said horizontal plane.

5. A tiltable game table comprising in combination, a board, obstacle means arranged in spaced relationship on said board, supporting means for said board, an intermediate member arranged between said board and said support, said intermediate member being pivotally connected to said board and said supporting means so as to allow longitudinal as well as lateral tilting movement of said board, first handle means associated with the ends of said board and operable to effect longitudinal tilting movement only of said board, second handle means arranged adjacent said first handle means but operable independently thereof and connected to said intermediate member for effecting lateral tilting movement only of said board, and means arranged in the longitudinal tilting path of said board to maintain said board at a minimum of inclination in the longitudinal direction thereof with regard to a horizontal plane, thereby preventing said board from being tilted into a horizontal plane.
